UNITED STATES PATENT OFFICE.

CHARLES JESDALE, OF CHICAGO, ILLINOIS, ASSIGNOR OF ONE-HALF TO MARTIN F. LUNOW, OF CHICAGO, ILLINOIS.

BOX.

Application filed November 8, 1918. Serial No. 261,608.

To all whom it may concern:

Be it known that I, CHARLES JESDALE, a citizen of the United States, residing at Chicago, in the county of Cook and State of Illinois, have invented a certain new and useful Improvement in Boxes, of which the following is a specification.

This invention relates to improvements in boxes and has for its object to provide a new and improved metal bound box which can be easily and cheaply manufactured and easily and quickly formed into shape when it is desired to use the box.

The invention is illustrated in the accompanying drawings, wherein

Fig. 1 is an exterior view showing the top, bottom and sides of the box united by metal strips;

Fig. 2 is a view of Fig. 1 as seen from the reverse side;

Fig. 3 is a view showing one end of the box;

Fig. 4 is an end view of the box when the parts are assembled;

Fig. 5 is a plan view of a piece of one of the metal strips;

Fig. 6 is a side view of the metal strips shown in Fig. 4;

Fig. 7 is a sectional view taken on line 7—7 of Fig. 1;

Fig. 8 is an enlarged sectional view taken on line 8—8 of Fig. 5;

Like numerals refer to like parts throughout the several figures.

In forming the box I take the top 1, bottom 2 and the two sides 3 and 4 of the box and place them in position as shown in Fig. 1. The top and bottom and sides of the box may be made each of a single piece or may each be made of several pieces if desired. The top, bottom and sides are then connected together by metal bands 5. These bands are strips of thin flat metal such as sheet iron or the like.

By means of dies or other agencies, fastening pieces 6 are struck from the metal at intervals, the fastening pieces being substantially at right angles to the strip as shown in Figs. 6 and 7. These fastening devices are therefore integral with the strips and at the points where they are cut away and bent laterally they leave the spaces 7.

In forming the box these fastening devices are forced into the top, bottom and sides and their ends are turned over or riv-

eted as shown in Fig. 8. The fastening of the metal strips to the top, bottom and sides may be done in any way desired, and I prefer to form them with a suitable machine for this purpose which will be the subject 60 matter of another application. The top, bottom and sides are left with small spaces 8 between them so that they may be readily folded into the form of the box. Near the ends of the top and bottom on the inside 65 thereof I fasten cleats 10, and near the ends of the sides I fasten cleats 9. The cleats 10 extend substantially the entire width of the top and bottom, while the cleats 9 are shorter than the width of the sides so that 70 when the box is folded, they will fit in between the cleats 10 as shown in Fig. 4. The ends 11 of the box are formed with the cleats 12 on the outside thereof.

In forming the box these ends are placed 75 in position and the box folded about them as shown in Fig. 4. The ends of the metal strip 5 project beyond the top and side of the box and may be bent to form interlocking parts 13 as shown in Fig. 4. If desired 80 the cleats 9 and 10 may be nailed or otherwise fastened to the cleats 12 at the ends of the box. By means of this construction I may make the box out of thin material and at the same time provide a very strong and 85 durable box which costs very little to make and which is capable of withstanding the strains and stresses to which such boxes are exposed. I may provide means for sealing the box against pilfering. This may be done 90 by providing holes in any one or more of the metal bands 5 at the point where they meet and then pass therethrough the seal 5^a. Any tampering with the box will require 95 the removal of this seal and thus will indicate that the box has been tampered with. The box can be used over a number of times by simply removing the seal and disconnecting the ends of the metal bands 5 and can be resealed each time it is used.

This construction also produces a box 100 which can be safely handled and which will not tear or injure the hands as the metal bands are flat and there are no staples or projecting parts to injure the hands, and the danger of injury is therefore eliminated. It will be noted that the fastening pieces 6 are struck from the metal at opposite edges of the bands so that some are at one edge and others at the other edge. This is an 110

important feature as it insures the holding down of both edges of the bands tightly against the box, and this therefore prevents these bands from catching on other boxes or other things when the boxes are being handled. Such a construction is also easier and cheaper to manufacture as the material to form the fastening pieces need only be cut along one line.

10 It will further be seen that I am able to make up the box without the necessity of using staples. I have described in detail a particular construction embodying my invention, but it is of course evident that 15 the parts may be varied in many particulars without departing from the spirit of the invention as embodied in the claims here-to appended, and I therefore do not limit myself to the particular construction shown.

20 I claim:

1. A box comprising a top, a bottom and two sides made of separated pieces, a plurality of strips of flat metal each having a plurality of fastening projections struck 25 from the metal at opposite edges thereof and integral with the strips, said fastening projections extending through the top, bottom and sides and having their ends bent over so as to fasten the strips in position, the 30 projections at the opposite edges of the strips holding both edges thereof tightly against said top, bottom and sides and fastening said top, bottom and sides together.

2. A box comprising a top, a bottom and 35 two sides, a plurality of strips of metal each having a plurality of fastening projections integral therewith, said fastening projections extending through the top, bottom and sides, and having their ends bent over so as to 40 fasten the strips to the top, bottom and sides, cleats near the ends of said top, bottom and sides and on the face opposite to that to which said strips of metal are fastened, said cleats having end faces substantially 45 at right angles to the cleat, two of said cleats being substantially equal in length to the width of the portions of the box to which they are attached, the other two cleats being shorter in length than the width of 50 the portions of the box to which they are attached, end pieces each having two cleats thereon shorter than the width of the end piece, said cleats arranged so that when the top, bottom and sides are folded around the 55 end pieces two of the cleats thereon engage the cleats of each end piece, and means for holding said top, bottom and sides in their folded position.

3. A box comprising a plurality of separated sections, a plurality of strips of flat 60 metal, said strips at intervals having inclined cuts which extend from each edge toward the center, the material on the outside of said cuts being bent at an angle to the strip with which it is associated, said 65 bent portions forming fastening projections which project into the sections of the box to bind the strips and sections together.

4. A box comprising a top, a bottom and 70 two sides, a plurality of strips of metal each having a plurality of fastening projections integral therewith, said fastening projections extending through the top, bottom and sides, and having their ends bent over so as to fasten the strips to the top, bottom 75 and sides, cleats fastened to said top, bottom and sides near the ends thereof, each cleat having flat end faces substantially at right angles to the cleat, two end pieces, cleats thereon, said top, bottom and sides 80 adapted to be folded about the end pieces the edges of the end pieces connecting on the inside of the cleats on the top, bottom and sides, some of the cleats on the top, bottom and sides engaging the cleats on the end 85 pieces.

5. A box comprising a top, a bottom and two sides, a plurality of strips of metal each having a plurality of fastening projections integral therewith, said fastening projections extending through the top, bottom and sides, and having their ends bent over so as to fasten the strips to the top, bottom and sides, cleats fastened to said top, bottom and sides near the ends thereof, two end pieces, 90 cleats thereon, said top, bottom and sides adapted to be folded about the end pieces the edges of the end pieces connecting on the inside of the cleats on the top, bottom and sides, and means for fastening the cleats on 100 the end pieces to the adjacent cleats on the other portions of the box, the ends of one or more of said strips of metal projecting beyond the portion of the box and disconnected therefrom when the parts are folded, 105 said projecting ends having disengaging spring interlocking parts which can be readily engaged and disengaged to open or close the box.

In testimony whereof, I affix my signature in the presence of two witnesses this 110 19th day of October, 1918.

CHARLES JESDALE.
